REAR SIGHT FOR FIREARMS

John C. Garand, Springfield, Mass.

Application October 23, 1942, Serial No. 463,024

6 Claims. (Cl. 33—56)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a rear sight for a firearm.

An object of this invention is to provide a rear sight for a firearm that may be conveniently and quickly adjusted for windage and elevation.

Another object of this invention is to provide a rear sight which will positively hold the sight settings regardless of any jarring due to firing or other causes.

The specific nature of this invention as well as other objects and advantages thereof will clearly appear from a description of a preferred embodiment as shown in the accompanying drawing in which:

Fig. 1 is a side elevational view of the rear sight.

Fig. 2 is a longitudinal sectional view of the rear sight shown in Fig. 1.

Fig. 3 is a top elevational view of Fig. 1 with aperture shown partially broken.

Fig. 4 is a cross sectional view taken along plane 4—4 of Fig. 3.

Fig. 5 is a left end elevational view of Fig. 1.

Fig. 6 constitutes a side and top elevational view of the aperture spring.

Fig. 7 is a top elevational view of the main leaf spring.

Fig. 8 is a fragmentary view on an enlarged scale of the aperture spring.

There is shown in Fig. 1 a rear sight embodying this invention comprising mainly a base 1, a leaf 5, an aperture 10, and a leaf spring 15. The aperture 10 is slidably mounted on the leaf 5 for elevation adjustment. The leaf 5 is in turn mounted on the base 1 in such a manner as to permit lateral adjustment for windage, such adjustment being obtained by lateral displacement of the leaf spring 15 which is pivotally secured to the base 1 and bears against the inside edges of the leaf 5, as will be presently described.

The base 1 is a long flat rectangular member. Approximately in the center of the base 1 there is provided on the top surface an integral upwardly projecting dovetailed portion 1a. In the center of the dovetailed projection 1a there is provided a hole 1b. The underside 1c of the base 1 is suitably milled to correspond to the arcuate surface of a firearm 2 as shown in Fig. 4. The base 1 is secured to the firearm 2 by a screw 3 which is inserted in the hole 1b and into a suitably threaded hole in the firearm 2. Near the forward

or right-hand edge of base 1 as viewed in Fig. 1 a small counterbored hole 1d is provided to receive a pin 3a. The counterbored portion of the hole is on the underside 1c of the base 1. The pin 3a has an integrally formed cylindrical head 3b which is inserted in the counterbored hole 1d of the base 1. The pin 3a projects slightly above the base 1 to secure a leaf spring 15 as will be presently described. On the upper surface of the base 10 at the rear or left-hand edge of the base 1 as viewed in Fig. 3 there are provided a series of short V-shaped serrations 4 which are formed on radial lines extending rearwardly from the axis of the hole 1d. These serrations are for windage 15 adjustment as will be described.

The leaf 5 is U-shaped and comprises a base 5a and integral upwardly projecting sides 5b and 5c on each side of the base 5a. The sides 5b and 5c are inclined upwardly at an angle from the base 20 5a towards the right as shown in Fig. 1. A dovetailed slot 5d is provided on the underside of the base 5a for mounting and securing the leaf 5 to the base 1. Integrally formed lugs 6 and 7 are provided along the upper edges of the sides 5b 25 and 5c respectively of the leaf 5. The lugs 6 and 7 project outwardly somewhat from the sides 5b and 5c respectively and are disposed at right angles thereto. Integral downwardly projecting stops 6a and 7a are provided on the forward or 30 right-hand end of the lugs 6 and 7 respectively, as viewed in Fig. 1. Approximately one-third of the distance of the base 5a from the right end of the leaf 5 as viewed in Fig. 3 there are provided integral projecting lugs 8 and 9 on the inside surface of the sides 5b and 5c respectively. The lugs 35 8 and 9 are positioned slightly above the base 5a so that the leaf spring 15 may be inserted thereunder to aid in securing leaf spring 15 as will be described. On the outer side 6a of the lug 6 there are provided a series of small U-shaped 40 notches 6d which are spaced in any desired increments of sight elevation adjustment. On the top surface 1c of the lug 7 there are provided transverse sight graduation markings 7b which 45 are spaced to correspond to the notches 6d.

An aperture 10 is slidably mounted on the lugs 6 and 7 of the leaf 5. The aperture 10 comprises an inverted U-shaped base 10a having depending arms 11 and 12 (Fig. 3) and an upwardly projecting circularly shaped eye-piece 10b. A peephole 10f is centrally provided in the eye-piece 10b. Inwardly projecting ribs 11a and 12a are provided on the arms 11 and 12 of the base 10a. The ribs 11a and 12a slidably engage the lugs 6 and 7 and 50 secure the aperture 10 to the leaf 5. On the out-

side edges of the arms 11 and 12 of the aperture 10 there are provided suitably serrated surfaces 10d and 10e to provide a convenient non-slipping grasping surface. A hole 10g is provided approximately in the center of the arm 11 of the aperture 10 extending obliquely downward through the arm 11 and adapted to be aligned with any one of the notches 6d on lug 6. When pin 14 is inserted in the hole 10g approximately one-half the diameter of the pin projects into one of the notches 6d. A small flat spring 13 is placed between the aperture 10 and the lug 7 of the leaf 5. A small downwardly projecting integrally formed lug 13a (Fig. 6) is provided on each end of the spring 13. The lugs provided on the spring 13 extend down into small vertical recesses formed in the lower corners of the rib 12a thereby securing the spring 13 against longitudinal displacement. Thus when the aperture 10 is mounted on the leaf 5 the central portion of spring 13 engages the side wall 5c and thus biases the aperture to one side so that the arm 11 of the aperture bears tightly but movably against the lug 6 of the leaf 5. When a force is applied to the aperture 10 by grasping the serrated surfaces 10d and 10e on the outside of the aperture 10 the pin 14 may be readily forced out of any of the U-shaped notches 6d permitting movement of the aperture to a new position along leaf 5. When latched, the bias of spring 13 will securely hold the aperture on the leaf 5 against displacement due to jarring or other causes because the projecting pin 14 firmly engages one of the U-shaped notches 6d.

A leaf spring 15 is pivotally mounted on the projecting end of pin 3a by engagement in a hole 15a. The spring 15 is preferably formed from flat stock and is provided with two integral outwardly projecting lugs 15b and 15c approximately in the center thereof (Fig. 7). A slight angular bend is provided adjacent to hole 15a to permit the spring to lie flat along the top of the base 5a of the leaf 5. The projecting lugs 15c and 15b of the spring 15 have rounded ends and are slidably inserted under the projecting lugs 8 and 9 provided on the inside of the arms 5b and 5c of the leaf 5. Thus lugs 8 and 9 hold the spring 15 firmly but movably in place. The other end of 15d of spring 15 is provided with a circular bend which projects downwardly and terminates in a series of serrations 15e which correspond to the V-shaped serrations 4 provided on the base 1. The spring action of the leaf 15 forces the serrations 15e provided on the end of the spring 15 to firmly engage corresponding serrations 4 on the base 1. Downwardly inclined surface 15f on the end 15d of spring 15 is suitably graduated for indexing the leaf spring for any windage adjustment desired.

This rear sight is quickly adjusted for elevation by grasping the aperture between the thumb and the index finger and sliding the aperture 10 along the leaf to the desired range setting as indicated by the graduations 7b provided on the leaf. Sight aperture 10 is securely held in the desired position as previously mentioned. Windage adjustment is easily obtained by moving the leaf spring 15 to either the right or the left after grasping and raising the downwardly projecting end 15f of the leaf spring 15 between the fingers. Spring tension in the leaf spring 15 securely holds the leaf 5 in the desired location on the rear sight base 1.

I claim:

1. A firearm sight comprising a base, a ramp

member mounted on said base for transverse movement with respect thereto, said member comprising a pair of upstanding walls having upwardly inclined top surfaces, a resilient member pivotally mounted on said base, said resilient member arranged to pass between said walls and to secure the ramp member to the base in any one of a plurality of positions laterally of the firearm, a sight aperture member slidably mounted on said upwardly inclined top surfaces, and detent means operative between the sight aperture member and the ramp member to secure the sight aperture member to the ramp member in any one of a plurality of positions vertically of the firearm.

2. A firearm sight comprising a base, a ramp member mounted on said base for transverse movement with respect thereto, said member comprising a pair of upstanding walls having upwardly inclined top surfaces, a resilient pivoted member engaging said walls and arranged to secure the ramp member to the base in any one of a plurality of positions, a sight aperture member slidably mounted on said upwardly inclined surfaces, there being a plurality of spaced notches on one of said walls, a detent in the sight aperture member engageable in any one of said notches, and resilient means between the other wall and the sight aperture member biasing said detent into engagement in said notches.

3. A firearm sight comprising a base arranged to be secured to a firearm, a U-shaped member slidably secured to said base for transverse movement thereon, the arms of said U-shaped member having upwardly inclined top surfaces, a leaf spring having one end pivotally secured to said base, said leaf spring passing between and engaging the arms of said U-shaped member to thereby secure the U-shaped member to the base in any one of a plurality of positions laterally of the firearm, sighting means slidably supported on the inclined top surfaces of the arms of said U-shaped member and means for resiliently securing said sighting means in a plurality of positions vertically of the firearm on said U-shaped member.

4. A firearm sight comprising a base arranged to be secured to a firearm, a U-shaped member slidably secured to said base for transverse movement thereon, the arms of said U-shaped member having upwardly inclined top surfaces, a leaf spring having one end pivotally secured to said base, said leaf spring passing between and engaging the arms of said U-shaped member and having its other end arranged to resiliently engage in any one of a plurality of transverse spaced notches in said base whereby said U-shaped member is secured to the base in any one of a plurality of transverse positions laterally of the firearm, sighting means slidably supported on the inclined top surfaces of the arms of said U-shaped member and means for resiliently securing said sighting means in any one of a plurality of positions vertically of the firearm on said U-shaped member.

5. A firearm sight comprising in combination, a ramp member arranged to be mounted on a firearm for transverse movement with respect thereto, a leaf spring member having one end portion arranged to be pivotally secured to the firearm, another portion overlying said ramp member and another end portion arranged to resiliently engage the firearm to thereby secure said ramp member in any one of a plurality of transverse positions with respect to the firearm, a sight

2,370,654

3

aperture member mounted on the ramp member, and detent means operative between said sight and aperture members to secure the former to the latter in any one of a plurality of positions vertically of the firearm.

6. A firearm sight comprising a base, a ramp member mounted on said base for transverse movement with respect thereto, a leaf spring member having one end portion pivotally secured to said base, a central portion overlying said ramp member and its opposite end portion constructed

5 to resiliently engage said base to thereby secure said ramp member in any one of a plurality of transverse positions with respect to said base, a sight aperture member slidably mounted on the ramp member, and detent means operative between said sight aperture member and said ramp member to secure the former to the latter in any one of a plurality of positions vertically of said base.

10
